UNITED STATES PATENT OFFICE.

MOSES S. BRUNDAGE, OF McCONNELL, ILLINOIS.

DESIGN FOR A CAP.

SPECIFICATION forming part of Design No. 21,712, dated July 12, 1892.

Application filed November 9, 1891. Serial No. 411,395. Term of patent 3½ years.

To all whom it may concern:

Be it known that I, MOSES S. BRUNDAGE, a citizen of the United States of America, residing at McConnell, in the county of Stevenson and State of Illinois, have invented and produced a new and original Design for Caps, reference being had to the accompanying drawings.

In said drawings, Figure 1 is a top plan of a cap bearing my design, and Fig. 2 is a front elevation thereof.

In the views, A is a cap whose crown is provided at its front and rear with peaks or visors A².

The leading feature of my design consists in a cap having upon its front visor and crown coats of arms, as shown.

Having now described and explained my design, what I claim as new, and desire to secure by Letters Patent, is—

The design for a cap, substantially as shown and described.

MOSES S. BRUNDAGE.
